(57) CLAIM

I claim an ornamental design for footwear, as shown and described.

DESCRIPTION

FIG. 1 is a perspective view of footwear, showing my new design;

FIG. 2 is a right side view of the footwear illustrated in FIG. 1;

FIG. 3 is a left side view of the footwear illustrated in FIG. 1; FIG. 4 is a front view of the footwear illustrated in FIG. 1; FIG. 5 is a back view of the footwear illustrated in FIG. 1; FIG. 6 is a top view of the footwear illustrated in FIG. 1; and, FIG. 7 is a bottom view of the footwear illustrated in FIG. 1. The broken lines illustrate environmental structure and form no part of the claim.
